UNITED STATES PATENT OFFICE.

PAUL CHOVANECZ, OF JOHNSTOWN, PENNSYLVANIA.

METALLIC RAILWAY-TIE AND RAIL-FASTENER.

1,198,417.

Specification of Letters Patent. Patented Sept. 19, 1916.

Application filed May 25, 1916. Serial No. 99,782.

To all whom it may concern:

Be it known that I, PAUL CHOVANECZ, a citizen of the United States, residing at Johnstown, in the county of Cambria and State of Pennsylvania, have invented certain new and useful Improvements in Metallic Railway-Ties and Rail-Fasteners, of which the following is a specification.

This invention relates to certain new and useful improvements in metallic railway ties and rail fasteners.

The primary object of the invention is the provision of a metallic railway tie provided with interlocking rail fasteners whereby the rails are securely positioned upon the tie without the employment of the usual spikes or bolts engaging the rails.

A further object of the device is to provide a metallic tie of simple construction provided with rail securing means adapted for bracing and strengthening the tie while operatively retaining the rails in a secure position thereon, the two rails upon the tie being readily released upon removing a single centrally positioned wedge bolt.

A still further object is to provide a metallic tie for positioning railway rails thereof with reinforcing means for the tie forming seats for the rails while securing members associated therewith are tensioned at different degrees of pressure in holding contact with the rails.

With these general objects in view and others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—Figure 1 is a side elevation of the present tie and rail fastener with track rails shown in transverse section operatively positioned thereon. Fig. 2 is a top plan view thereof. Fig. 3 is a central longitudinal vertical sectional view of the same. Figs. 4, 5 and 6 are transverse vertical sectional views taken respectively, upon line IV—IV, V—V and VI—VI of Fig. 3. Fig. 7 is a detail sectional view taken upon the line VII—VII of Fig. 3. Fig. 8 is a perspective view of slightly more than one-half of the present form of tie. Fig. 9 is an inverted perspec-

tive view of the locking plate. Fig. 10 is a perspective view of the flange lock. Fig. 11 is a perspective view of the reinforcing seat. Fig. 12 is a perspective view of the 60 rectangular washer, and Fig. 13 is a perspective view of the wedge bolt employed with the device.

The metallic tie 10 forming a part of the present invention is of the general shape of 65 a channel bar having opposite parallel sides 11 while the connecting base or portion 12 of the tie has oppositely projecting side flanges or marginal portions 13, the said base 12 with its flanges 13 being adapted to 70 rest flatly upon the road bed while the ballasting thereof may be filled in over the said flanges if found desirable.

A table shaped member 14 serving the combined purpose of reinforcing the tie and 75 forming a seat for the rails is arranged with a seating board 15 adapted for sliding longitudinally upon the upper edges 16 of the tie sides 11 and having parallel depending legs 17 adapted to overlie the sides 11 having inwardly projecting ribs or feet 18 slidably received within longitudinal grooves 19 upon the outer faces of the sides 11 at points adjacent the base flanges 13. The table member 14 may be readily slid in- 80 wardly over either end of the tie 10 until further movement is prevented by means of the shoulders 20 at the inner ends of the grooves 19 being engaged by the table feet 18 and at which time oppositely arranged 90 notches 21 of the tie sides 11 will be spaced slightly outwardly of the said table. The flange lock 22 is then positioned with its body-portion 23 transversely arranged with- 95 in the notches 21 being provided with an inwardly projecting block 24 between the sides 11 and lying flush with the edges 16, whereby the table 14 may be shifted outwardly upon the tie 10 until the top 15 flatly engages the inner face of the said body 23 100 which will prevent the flange lock 22 from being removed, it being understood that the said flange lock has an inwardly projecting flange 25 overlying the table top 15. A rail such as 26 may then be positioned upon the table top 15 with one base flange 27 of the rail beneath the said flange lock member 25 at which time the locking plate 28 may be slidably positioned upon the tie side edges 16. A depending block 29 carried by the 110 plate 28 fits between the tie sides 11 while an end flange 30 of the plate 28 is oppositely

arranged and spaced from the block 29 allowing the plate to be positioned receiving the adjacent edge of the table top 15 and the rail flange 31 between the said block 5 29 and plate flange 30, as best illustrated in Fig. 3 of the drawings.

It will be understood that both of the rails 26 are provided with similarly although oppositely positioned fastening devices to 10 that just described, the inner ends 32 of the locking plates 28 being formed with substantially U-shaped recesses 33, having beveled sides 34, the said plate ends being slightly spaced apart when operatively positioned upon the tie.

The tie sides 11 are centrally provided with alining cut-away portions 35 adapted for the reception of a rectangular washer 36 having a central perforation 37 to receive 20 the threaded shank 38 of a wedge bolt 39 having a rectangular head 40 provided with inclined lateral edges 41 having wedging engagement with the plate recessed edges 34 when the wedge bolt is operatively positioned, a tensioning lock nut 42 being provided for securing the bolt 39 in locked arrangement with the washer 36 and the tie sides 11.

The present detailed description of the 30 invention includes the manner of assembling the entire device and a further description of the operation is therefore unnecessary. The rails 26 are readily released from the tie 10 by first removing the nut 42, thereby 35 allowing the wedge bolt 39 to be separated from the locking plates 28 which plates may then also be detached. The rails 26 are thus released and upon being removed, the tables 14 as well as the flange locks 22 may be separated 40 from the tie 10 leaving the latter positioned upon the road bed.

An advantageous metallic tie is thus arranged having interlocking rail fastening devices which strengthen the tie during the 45 operation of the railroad employing the same and while the present form of the device is believed to be preferable, minor changes may be made if desired.

What I claim as new is:—

- 50 1. A railway tie and rail fastener comprising a channel bar having laterally projecting base flanges, the sides of the said bar having longitudinal grooves upon their outer faces adjacent the said flanges forming abutment shoulders at their inner ends, a combined tie reinforcing and rail supporting table slidably mounted upon the said bar sides, depending legs provided upon the said table and having inwardly projecting ribbed feet 55 slidably arranged within the said grooves, opposite flange locking members for the rail carried by the said tie sides extending beneath the said table and operatively arranged, and a removable locking 60 means for one of the said locking members.
2. A railway tie and rail fastener comprising a channel bar having laterally projecting base flanges, the sides of the said bar having longitudinal grooves upon their outer faces adjacent the said flanges forming 65 abutment shoulders at their inner ends, a combined tie reinforcing and rail supporting table slidably mounted upon the said bar sides, depending legs provided upon the said table and having inwardly projecting 70 ribbed feet slidably arranged within the said grooves, the said table being adapted for the seating reception of railway rails thereon and the tie sides having opposite notches outwardly of the said table, a flange 75 lock positioned within the said notches, a block upon the said flange lock between the said sides and arranged beneath the said table when operatively arranged in engagement with the said lock, an inwardly projecting rail engaging flange upon the said lock above the said table, a locking plate 80 shiftably mounted upon the said tie sides inwardly of the said table, rail and table engaging means upon the said plate, and a 85 locking bolt for the said plate.
3. A railway tie and rail fastener comprising a channel bar having laterally projecting base flanges, the sides of the said bar having longitudinal grooves upon their 90 outer faces adjacent the said flanges forming abutment shoulders at their inner ends, a combined tie reinforcing and rail supporting table slidably mounted upon the said bar sides, depending legs provided upon the said 95 table and having inwardly projecting ribbed feet slidably arranged within the said grooves, the said table being adapted for the seating reception of railway rails thereon and the tie sides having opposite notches 100 outwardly of the said table, a flange lock positioned within the said notches, a block upon the said flange lock between the said sides and arranged beneath the said table when operatively arranged in engagement 105 with the said lock, an inwardly projecting rail engaging flange upon the said lock above the said table, a locking plate shiftably mounted upon the said tie sides, a depending block carried by the said plate between 110 the said tie sides and projecting beneath the said table when operatively arranged, a rail engaging flange carried by the said locking plate opposite to and spaced from the said plate block and overlying the said table 115 when operatively positioned, the said plate having a recess in its inner end provided with an inclined side, and a wedging lock bolt arranged within the said recess in contact with the said side when the device is 120 operatively arranged.
4. A metallic tie and rail fastener comprising a channel bar having transverse notches and longitudinal grooves in its opposite end portions and further provided 125 130

with centrally positioned alining cut-away portions, reinforcing supporting tables shiftably mounted upon the said bar in sliding engagement with the said grooves, 5 rail locking members within the said notches in interlocking arrangement with the said tables, rail locking plates mounted upon the said bar in engagement with the said tables at their outer ends and having recesses in 10 their spaced inner ends provided with oppositely positioned beveled sides, a wedge bolt having the head thereof positioned within

the said recess and arranged with inclined faces seated upon the said beveled sides, a rectangular washer arranged between the 15 said sides of the said channel bar within the central cut-away portions thereof with the shank of the said bolt extending therethrough when the device is operatively positioned, and a tensioning locking nut upon 20 the said shank beneath the said washer.

In testimony whereof I affix my signature.

PAUL CHOVANEZ.
